UNITED STATES PATENT OFFICE.

WILLIAM A. BERNARD, OF DANVILLE, VIRGINIA.

COMBINED NAIL AND EAR CLEANER.

SPECIFICATION forming part of Letters Patent No. 324,001, dated August 11, 1885.

Application filed May 21, 1884. (No model.)

To all whom it may concern:

Be it known that I, WILLIAM A. BERNARD, a citizen of the United States, residing at Danville, in the county of Pittsylvania and State 5 of Virginia, have invented certain new and useful Improvements in Combination-Tools, of which the following is a specification, reference being had therein to the accompanying drawings.

10 My invention relates to a combined pocket-tool; and the novelty consists in the construction and arrangement of parts, as will be more fully hereinafter set forth, and specifically pointed out in the claims.

15 The object of the invention is to provide a peculiar combination of tools—such as nail or thread cutters, nail-files, ear-spoon, a cord or nail knife, a shoe-buttoner, an untying-hook, and a needle-threader, and the like—into such 20 small and compact form as that the whole may be readily carried in the pocket, and the peculiar tools are arranged to be of importance to either sex.

25 This invention contemplates more than the mere collocation of several tools or utensils into a compact form. It seeks to give to each utensil or tool an additional function—a function that arises by reason of the arrangement of parts over and above the legitimate function 30 of the tool itself—as, for instance, I make the shoe-buttoner serve also as an operating-lever for the cutters, and the ear-spoon serve as a spring-guide for the needle when the needle-threader is in service.

35 The device as a whole is a convenient adjunct to a lady's work-basket, to a toilet-set, or to the paraphernalia of a desk or office. It is of much importance as a pocket utensil for the person of leisure, whether man or woman, 40 and is valuable to artisan, mechanic, seamstress, or professor.

45 The invention is fully illustrated in the accompanying drawings, which form a part of this specification, and in which—

50 Figure 1 is a top plan view of the device, showing the shoe-buttoner and knife-blade folded out of use. Fig. 2 is a reverse or bottom plan view showing the ear-spoon and hook in the same position. Fig. 3 is a side elevation with all the tools extended, parts being broken away to show the internal construc-

tions. Fig. 4 is a side elevation showing the button-hook arranged to serve as a lever for the cutters, the dotted lines indicating the operation. Fig. 5 is a detail section showing 55 the arrangement of parts for the needle-threader with the ear-spoon in elevation acting as a spring-guide to hold the needle in its transverse slot-guide. Fig. 6 is a detail section showing the relation of the spoon and its seat 60 with the spring-arm, and showing the means for holding said spoon open or closed; and Fig. 7 is a perspective end view showing the form of the cutters and the construction of the body of the ear-spoon and base. 65

For convenience, the uses and operation of the several parts will be given as the said parts are described by letter.

Referring to the drawings, in which similar letters of reference indicate like parts in all 70 the figures, A designates the base or body, and B the spring-arm rigidly secured thereto. These parts bear upon each other for about one third of their area, thus leaving a portion of the arm B to be sprung inward at will. The 75 body A has a curved cutting-edge, G', upon one end, and the corresponding end of the spring-arm B has a straight cutting-edge, G, which edges, when brought together by the arm B being sprung toward the base A, serve 80 to give a draw-cut upon the finger-nail, or whatever else it is desired to operate upon. The side edges of the base are formed into a file, S, and the body A is cut away at b in such manner as to afford room for the hook D to be 85 folded upon the arm B, and the hook and body at this point approximate the general contour of the arm B.

The hook D is hinged or pivoted at d, and has a bearing-shoulder, d', which abuts against 90 the stop-shoulder d'', formed on the base A, when the said hook is open for use; and the said base is cut away or recessed at b' to allow the nail of the operator to be inserted to open the hook. This hook is of great value, 95 as for untying knots, pulling a cork, cleaning the finger-nails, &c., and is a valuable adjunct to the complete device. When out of use, it folds neatly out of the way, and, being of the same thickness as the base, folds closely against 100 the same.

In the bottom surface of the base A is formed

a transverse guide-slot, H, from the termination of which a hole, h, connects with a conical recess, h', formed in both base and arm at this point.

5 Pivoted at c to base A is an ear-spoon, C, the shank of which has an inherent spring action, and the spoon end of this device is adapted to extend across the slot H. Thus when the spoon is closed out of use it forms a 10 spring-guide, under which a needle may be inserted, the spoon springing to allow different-sized needles to be manipulated. The eye of a needle being turned until it registers with the hole h, a thread end may be inserted into 15 the recess h', and the inclined sides will guide it through the needle-eye, the spoon meanwhile serving to hold the needle properly positioned for such operation. This double function of the spoon in this device makes it especially important to seamstresses and housewives.

The ear-spoon has upon its under surface a longitudinal ridge or projection, c², which when the spoon is open or closed operates in a 25 longitudinal slot, b³, formed in the base A to lock the said spoon against any ordinary displacement; but the spoon in being opened or closed by force will cause the said projection to ride up the sides of the slot b³, as the spring 30 of the arm B allows it, and the said spoon may be turned until the projection again registers with the slot, when it will snap into place, and the parts be held thus conditioned by the constant force of the spring- 35 arm B. This force is exerted through the stud I, which stud is headed upon the outside of the spoon, and passes loosely through both base and arm, its upper end having a pivotal connection, f, with the button-hook F. 40 This button-hook F has a fulcrum-shoulder, f', and the pivot f is so arranged that the said hook may be turned until said shoulder f' rests upon the outer face of the arm B, the said arm springing in for that purpose. This position 45 is indicated in Fig. 4, where the button-hook may be employed as a lever for working the cutting-jaws G G'. Thus the spring-arm B not only serves to force the cutting-edges apart, but by its connections to lock the ear-spoon in either an open or closed position. 50 It also holds the button-hook in the lever position shown in Fig. 4, and in its closed position, as shown in Fig. 1. In the latter position it is locked from accidental displacement by 55 its hook fitting over a stud, e, which stud also serves as the pivot of a knife-blade, E.

The arm B is bent, as shown at b⁴, at the junction of its spring-arm with the bearing position, and this form provides for the knife-blade E to occupy the space under the button-hook when the same is closed, the knife-blade lying under the hook end, and its pivot e serving as a lock-stop for said hook.

The arm B has a bearing-stud, e², against 60 which the shoulder e' of the blade abuts when the same is in use, the same stud acting as an

abutment for a shoulder, e³, on the knife-blade to prevent said blade from passing beyond its position under the hook F when the same is closed.

The operation, from the foregoing description, is obvious. Modifications may be made in details of construction without departing from the principle or sacrificing the advantages of my invention, the essential feature of 75 which will be readily understood—as, for instance, very slight changes in the construction of some of the parts might adapt them to wider uses, and other parts having different uses may be added. The button-hook may be 80 replaced by a corkscrew, and the cutting-edges G and G' may be made pinchers or tweezers.

I attach importance to the multiplicity of functions imparted to the arrangement—as the spring of the arm B serving to hold the spoon 85 locked in either an open or closed position, to retract the cutting-jaw, and to hold the hook F in either of the two positions; or the spoon acting to hold different sized needles in the 90 threading device, as well as serving its legitimate function as a spoon; or the knife-blade pivot acting as a lock-stop to the button-hook; or the button-hook acting additionally as a lever for the cutters.

The cutting-edges may be readily adjusted 95 to each other by means of the screw which secures the parts A B together, the said screw passing through an elongated slot in the part B.

What I claim as new is—

1. The combination of the base A, spring-arm B, having conical recess h', and slot H, as shown, and the spoon C, as and for the purposes set forth.

2. The combination of the base A, spring-arm B, as described, the spoon C, having ridge c², and the stud I, as and for the purposes set forth.

3. The combination of the arm B, bent at b⁴, and the blade E, with the pivot e and hook F, the said pivot serving as a lock-stop for said hook, as set forth.

4. The combination of the part A, cut away at b, and having recess b', the hook D, having shoulder d', and the arm B, as set forth.

5. The combination of the base A, having slot b³ and cutter G', the spring-arm B, having cutter G, the spoon C, having ridge c², the stud I, and the button-hook F, as and for the purposes set forth.

6. The combination of the base A, having files S, slot H, and cutter G', the arm B, having cutter G, the spoon C, having ridge c², the stud I, hook F, pivot f, blade E, and pivot e, as and for the purposes set forth.

In testimony whereof I affix my signature in presence of two witnesses.

WILLIAM A. BERNARD.
